UNITED STATES PATENT OFFICE

ARTHUR MALLING, OF CLEVELAND, OHIO, ASSIGNOR TO THE SCHWENGER-KLEIN COMPANY, OF CLEVELAND, OHIO, A CORPORATION OF OHIO

REFRIGERATOR COUNTER

Application filed February 13, 1928. Serial No. 254,021.

My invention relates to refrigerator counters adapted for the display of such perishable food stuffs as meats and the like and has for its object the improvement in the structure of such a device which will eliminate certain difficulties such for instance as the danger of breakage of the top of the counter.

It is also a purpose of this invention to provide in connection with the refrigerator counter of this character means for illuminating the interior thereof without subjecting the interior to the heat given off by the illuminating device.

15 A further object of the invention is to provide a novel platter rack for holding the meat platters within the refrigerator counter so as to avoid having the platters strike the front of the counter and to aid in providing 20 the proper spacing for free circulation of air about the articles placed within the counter.

It is also an object of this invention to provide the cooling chamber with an enamelled steel floor having novel means for connecting the adjacent sheets of material used together.

Other objects and advantages of the invention will appear as the description proceeds when taken in connection with the accompanying drawings. However, I wish it to be distinctly understood that I do not intend to limit myself to the exact details shown and described, but that I intend to avail myself 35 of all such modifications as would occur to one skilled in this art and as fall within the scope of the claim.

In the drawings:

Fig. 1 is a cross sectional view taken transversely through my improved refrigerator counter;

Fig. 2 is a perspective view of the refrigerator counter;

Fig. 3 is a plan view of the novel platter 45 rack;

Fig. 4 is a side elevation of the platter rack; and

Fig. 5 is a section on line 5—5 of Fig. 2.

Referring now in detail to the drawings, 50 the numeral 5 indicates generally a support-

ing base for the counter having at the top thereof the floor 6 serving as the floor of the refrigerating chamber. This floor as shown is made up of the insulating section 7 preferably made of cork board, the supporting section 8 which may be of any suitable material and on top of this the enamelled steel plate 9 which as shown turns up at its opposite sides at 10 and 11 to form a good joint with the side walls 12 and 13 of the refrigerator. The rear wall 12 extends vertically upward a short distance and is insulated by means of cork board similar to that used at 7 in the floor.

If the sheet 9 is of very great length it is 65 difficult to make and also has the objectionable property of expanding and contracting under changes of temperature which may cause loosening of the joints between it and the walls at the ends of the counter. To 70 avoid this the sheets may be constructed as shown in Fig. 5 and a plurality of sheets used. The adjacent edges of sheets 9 and 9' are flanged up as at 35 and 36. The nickel silver inverted channel 37 fits down over the 75 flanges 35 and 36 and is secured to the floor beneath by means of screw 38 and supported by the member 39. Suitable packing as indicated at 40 is also used to fill the space between the flanges 35 and 36 and member 39. 80 It is evident that this structure permits the plates 9 and 9' to move toward and away from each other as they expand and contract without opening a space between them or pulling themselves away from the end 85 walls.

Resting on top of the wall 12 is a combined cover member and work table 14 which when in place serves as a table on which the meats or other articles may be wrapped or 90 trimmed and which may be lifted upwardly to permit access to the refrigerant holding tanks 15. Brackets 16 project rearwardly from the wall 12 to aid in the support on the table 14.

Within the brine tanks 15 which are supported above the enamelled plate 9 are provided suitable drainage valves indicated generally by the numeral 17 for draining the liquid out of the tanks whenever desired. 100

The tanks 15, of course, are supported above the floor 9 by means of the supporting members 18 so as to permit free circulation of air therearound.

5 The front wall 13 as shown is inclined rearwardly and is made up of a plurality of transparent panes 19, 20, and 21 with air spaces therebetween so as to provide a good insulation. The frame member 22 is provided 10 at the forward end of the cover member 14 and this frame member serves the dual purpose of supporting one edge of the member 14 and the lower edges of the sliding doors 23 and 24 which are also provided with a plurality of insulating panes indicated generally at 25 of transparent material.

At the top of the frame member 22 which carries sliding doors and which is inclined forwardly, the cover member 26 is provided. 20 This cover member 26 as shown overlaps the top of the frame 22 at 27 and in addition is bent down over the top of the front wall 13 as at 28 so that it serves not only as a cover, but as means for bracing and holding the 25 frame 22 and front wall 13 together. This top member is preferably made of white porcelain enameled steel so that it cannot be broken by persons leaning thereon or dropping heavy articles on the counter and at the 30 same time it will present a clean and pleasing appearance. A layer of cork board 29 also serves to insulate the chamber at this point.

In order to illuminate the interior of the 35 counter I provide at the front thereof adjacent the top a plurality of porcelain enamel reflectors 30 and 31 which have suitable means therein for supporting and connecting a lighting unit to a source of current and 40 embedded in the upper frame section of the front wall there is provided a conduit 32 for conducting the current to the lighting unit within the reflector. This conduit is extended around the end 33 of the counter where 45 a plug 34 is provided for connection by means of a suitable cord to the house wiring. By this provision, it will be seen that while the reflectors 30 and 31 direct the light into the refrigerating chamber, the heat given off by 50 lighting means is kept outside of the chamber so that it does not tend to heat up the interior thereof and thus reduce the efficiency.

Suitable wire trays 41 are provided within 55 the refrigerating chamber for supporting the platters or pans containing the article to be displayed. These wire trays are illustrated more clearly in Figs. 3 and 4. They consist of the frame member 42 having the portions 43 and 44 bent downwardly to form supporting legs for one end of the tray. Front legs 45 are welded or otherwise secured to the lower face of 42 and a cross brace 46 serves to give added strength to the structure. The bars 47 extend lengthwise of frame 42 and 60 are secured thereon as by welding or other

suitable manner to provide a supporting surface. Certain of these bars are U-shaped and have the connecting portion between the two legs of the U-shaped member extended beyond the frame as at 48 and 49 to form stops 70 or bumpers to hold the tray away from the front wall. Certain other members 47 as indicated at 50, 51 and 52 have the ends which are connected together turned up to form stops to prevent the platters placed on the 75 rack from sliding forward against the front wall of the cooling chamber.

From the above description it is thought the construction and advantages of this device will be clear to those skilled in this art 80 and having thus described my invention what I claim as new and desire to secure by Letters Patent of the United States is:

A platter rack for refrigerator counters comprising a frame member having supporting legs thereon for supporting said rack with one end higher than the other, spaced bars extending longitudinally of and secured on said frame and certain of said bars having portions thereof extending beyond said 90 frame at said lower end to form abutments to maintain said tray spaced from the wall of the counter, certain other of said bars having the ends at the lower end of said tray turned up to prevent platters from sliding 95 beyond the end.

In witness whereof, I hereunto subscribe my name this 19 day of January, A. D. 1928.

ARTHUR MALLING.
